(57) **CLAIM**

The ornamental design for a loudspeaker including mounting bracket, as shown and described.

DESCRIPTION

FIG. 1 is a front perspective view of a loudspeaker including mounting bracket showing our new design;

FIG. 2 is an enlargement of the portion of FIG. 1 that is encircled by a dash-dot-dash line labeled as FIG. 2;

FIG. 3 is a top plan view thereof;

FIG. 4 is a bottom plan view thereof;

FIG. 5 is a front elevational view thereof;

FIG. 6 is an enlargement of the portion of FIG. 5 that is encircled by a dash-dot-dash line labeled as FIG. 6;

FIG. 7 is a rear elevational view thereof;

FIG. 8 is a right side elevational view thereof;

FIG. 9 is an enlargement of the portion of FIG. 8 that is encircled by a dash-dot-dash line labeled as FIG. 9;

FIG. 10 is a left side elevational view thereof; and,

FIG. 11 is an enlargement of the portion of FIG. 8 that is encircled by a dash-dot-dash line labeled as FIG. 11.

In the drawings, broken lines represent the environment of the design and form no part of the design. The dash-dot-dash reference lines in FIGS. 1, 5, 8, and 11 form no part of the claimed design.
